[57] **ABSTRACT**

A method and device for undulating a fabric sheet near the fell front so as not to cause the weft yarn to come into contact with the same portion of a dent. The device comprises a cross bar positioned below and in contact with the fabric sheet transversely to the same near the fell front. Rotation of the cloth roller causes an undulating motion of the cross bar so that the fabric sheet is undulated near the fell front, whereby the points of contact between the weft yarn and the dent during beating differs from time to time. In another embodiment, the cross bar is drivably coupled with the shaft of a friction roller by means of an angled rod in such a manner that rotation of the friction roller causes an undulating motion of the cross bar.

**METHOD OF PREVENTING A DENT FROM BEING
DAMAGED BY A WEFT YARN DURING BEATING
AND THE DEVICE FOR ACCOMPLISHING THE
SAME**

This invention relates to the beating of a weft yarn and more particularly to a method of preventing a dent from being damaged by the weft yarn during beating and the device for accomplishing the same.

In a conventional loom, beating is effected by causing the reed to move a predetermined length of weft in its straightened state to the fell front, with the length of weft kept in contact with substantially the same portion of the dent of the reed. Thus, the dent tends to be damaged only at that particular portion contacted by the weft yarn. In case where a hard thread such as one made of polyester fiber is used as a weft yarn, the dent becomes unusable after as short as 1,000 to 2,000 meters of cloth has been produced.

It is therefore an object of this invention to provide a new and improved method of preventing a dent from being damaged by a weft yarn during beating.

It is another object of this invention to provide a device for accomplishing the above method.

It is a further object of this invention to provide a device in which the fabric sheet is undulated near the fell front so as not to cause a weft yarn to come into contact with the same portion of the dent.

In the drawings:

FIG. 1 is a schematic view of a loom incorporating the present device;

FIG. 2 is a detailed view of the present device as shown in FIG. 1; and

FIG. 3 is a fragmentary view showing another embodiment of this invention.

Referring now to FIG. 1, there is illustrated a loom incorporating the present device. The loom has a warp beam 10 from which a warp array 11 is drawn off to a heald 12 by way of a back rest roller 13. As is well known, the heald 12 serves to have upper and lower portions 14 and 15 of the parallel warp array 11 extending in their tensioned state so as to form a shed 16 therebetween. Provision of a shuttle or an injection nozzle (not shown) is made for inserting a predetermined length of weft 17 into the warp shed 16. The loom also includes a reed 18 which is operated to beat the length of weft 17 so as to produce a fabric sheet 19 immediately after the length of the weft 17 has been inserted into the warp shed 16. The fabric sheet 19 thus woven is supplied through a friction roller 20 to a cloth roller 21, where the sheet 19 is wound thereon.

According to the teachings of the invention, cam means 22 is provided whose shaft 23 is drivably coupled with the shaft 24 of the cloth roller 21 by means of a belt 25. Other coupling means such as a gearing may be used. Disposed above the cam 22 is a plunger 26 mounted in a stationary bracket 27 for reciprocating movement in the vertical direction. As is best shown in FIG. 2, the plunger 26 has attached to the lower end thereof a cam follower 28 which is kept in rolling contact with the cam surface of the cam 22, so that the plunger 26 is moved up and down as the cam 22 is rotated. Attached to the other end of the plunger 26 is a cross bar 29 which extends below and in contact with the fabric sheet 19 transversely to the same over its entire breadth so as to support it at a location immediate-

ly adjacent the fell front 30. Thus, rotation of the cam 22 causes an undulating motion of the fabric sheet 19 near the fell front 30. While the cross bar is shown as supporting and undulating the fabric sheet, it is to be understood that the cross bar could be replaced by a temple bar (not shown) which is directly coupled with the plunger.

In operation, the cloth roller 21 is rotated to wind the fabric product 19 thereon and simultaneously to rotate the cam 22. Rotation of the cam 22 causes the cam surface to be raised from the position represented by the solid line 31 of FIG. 2 to that of the dotted line 32. As a result, the plunger 26 having the cross bar 29 attached to the top thereof is moved upwards, lifting the fabric sheet 19 to the position represented by the dotted line 33. As the cam 22 is further rotated, on the other hand, the plunger 26 is caused to move downwards by a downward force exerted by the tensioned fabric sheet 19. Thus, the fabric sheet 19 lowers itself together with the plunger 26 up to the position as represented by the solid line 34. In this way, rotation of the cloth roller 21 results in undulation of the fabric sheet 19. Since the cross bar 29 is positioned below the fabric sheet 19 immediately adjacent the fell front 30, the fell front 30 is undulated, so that the points of contact between the weft yarn 17 and the dent 35 of the reed 18 during beating differs from time to time. Therefore, there is little possibility of the dent 35 being damaged only at that particular portion contacted by the weft yarn 17 during beating.

FIG. 3 is a fragmentary schematic view showing another embodiment of this invention which is different from that of FIG. 1 in that the cross bar is moved up and down by rotation of the friction roller 20. In this preferred embodiment, the friction roller 20 has a cam 36 attached to the shaft 37 thereof. The cam 36 has a cam surface with which a cam follower 38 is kept in rolling contact. The cam follower 38 is attached to one end of an angled rod 39 pivotally mounted in a loom frame as shown at 40. The angled rod 39 has attached to the other end thereof a cross bar 41 which is positioned in a manner to extend below and in contact with the fabric sheet 19 transversely to the same immediately adjacent the fell front 30. In operation, rotation of the friction roller 20 causes a pivotal movement of the angled rod 39, so that the fabric sheet 19 is undulated by the cross bar 41 attached to the angled rod 39.

In the embodiments as shown in FIGS. 1 and 2, since a downward force is applied to the cross bar by the tensioned fabric sheet, the vertical position of the cross bar is related to the rotational angle of the cam even when the cross bar is being lowered. Therefore, by modifying the shape and size of the cam it is possible to control the vertical displacement of the cross bar. Although the cross bar as shown is undulated by rotation of the cloth roller or friction roller, it is to be noted that other means for driving the cross bar for undulation can be used. In this instance, it is desirable that the cross bar is driven by such means as rotating at a relatively low speed, because the cross bar is undulated at a relatively long period.

What is claimed is:

1. A device for preventing a dent from being damaged by a weft yarn, comprising a cross bar positioned below and in contact with a fabric sheet trans-

versely to the same and located immediately adjacent to the fell front, and means operatively connected to said cross bar for undulating the same together with the fabric sheet so as not to cause the weft yarn to come into contact with the same portion of the dent at each beat-up, said means comprising a plunger mounted in a stationary bracket for reciprocating movement in the vertical direction and having one end operatively connected to said cross bar, a cam follower attached to the other end of said plunger, a cam having a cam surface with which said cam follower is kept in rolling contact, and a driving means for causing said cam to rotate, whereby the points of contact between the dent and the weft yarn during beating differs from time to time.

2. A device according to claim 1, in which said driving means comprises a belt for drivably coupling the shaft of a cloth roller with that of said cam.

3. A device according to claim 1, in which said driving means comprises a belt for drivably coupling the shaft of a friction roller with that of said cam.

4. A device for preventing a dent from being damaged by a weft yarn, comprising a cross bar positioned below and in contact with a fabric sheet trans-

versely to the same and located immediately adjacent to the fell front, and means operatively connected to said cross bar for undulating the same together with the fabric sheet so as not to cause the weft yarn to come into contact with the same portion of the dent at each beat-up, said means comprising an angled rod pivotally mounted in a loom frame and having one end attached to said cross bar, a cam follower attached to the other end of said angled rod, and a cam mounted on the shaft of a friction roller for rotation therewith and having a cam surface with which said cam follower is kept in rolling contact, said friction roller engaging with said fabric sheet which is supplied to a cloth roller and which is wound thereon and being slightly rotated when a beat up is completed by said dent, the cam surface of said cam being a locus of a point which moves as a distance between the point and the axis of said cam is continuously slightly varied thereby slightly undulating the fabric sheet when a beat up is completed by said dent, whereby the points of contact between the dent and the weft yarn during beating differs from time to time.
